UNITED STATES PATENT OFFICE.

HERBERT M. FRIENDLY, OF PORTLAND, OREGON.

TELEPHONE SYSTEM.

Application filed May 16, 1921. Serial No. 469,886.

To all whom it may concern:

Be it known that I, HERBERT M. FRIENDLY, a citizen of the United States, residing at Portland, in the county of Multnomah and 5 State of Oregon, have invented a certain new and useful Improvement in Telephone Systems, of which the following is a full, clear, concise, and exact description, reference being had to the accompanying drawings, forming a part of this specification.

The present invention has for its broad objects, the improvement of telephone systems in general and more particularly automatic and semi-automatic systems, looking 15 toward the affording of operative conveniences to users and switching attendants which have been heretofore unknown.

The invention in the specific form chosen for the illustration herein, contemplates a 20 so-called two-wire common battery automatic telephone system as has been widely used, the present invention necessitating novel departures from equipments heretofore known, in attaining certain new objects, 25 while retaining certain operative functions which are known.

The exemplified form of the present invention chosen to illustrate it contemplates its 30 adaptation to a comprehensive automatic telephone exchange system, and has for a salient object the enabling of an attendant, or other party who has received a call from a subscriber, to transfer or pass the connection to further connection or connections. 35 For example, a subscriber calls the information operator by the usual automatic means, and, upon the response of the attendant, informs the latter with whom he wishes to communicate. The attendant, after ascertaining the telephone number of the wanted 40 subscriber so informs the calling subscriber. Then, the calling subscriber may release the connection and re-initiate the call, directing it to the proper telephone number through 45 the agency of the usual automatic means, or, as contemplated in the present invention, the attendant can, through the agency of a dial calling device or a pre-setting calling device, transfer or pass the connection directly from the calling subscriber's to the 50 wanted subscriber's telephone and release the equipment leading to the attendant's switchboard, thus leaving it free, and there-

fore, again seizable to other calling subscribers. 55

The present invention, in its illustrated form contemplates not only means for forwarding the call to the wanted line, but also contemplates controlling and supervising the connection in various ways as will appear. The present invention, as will appear, 60 contemplates as one of its objects the establishment of a direct path between the calling and the wanted telephones when switched by the attendant, regardless of the location 65 of the attendant as relates the location of the calling and the wanted telephones in the exchange.

Another object of the present invention is to afford means so the said attendant can 70 continue the connection through a terminating switching cord and plug, or through a set of independent companion cords and plugs. These adaptions would be employed where it is desired to continue the connection 75 to a manual switching means, or through a combination of automatic control and manual switching. The invention is also applicable to automatic private branch exchanges. 80

The present invention, therefore, has wide adaptations, and moreover, would in many instances involve a different application for the same nominal use in the same exchange, depending, for example, upon the location 85 of the attendant's switchboard with relation to the calling telephone in a multi-office exchange system. That is to say, whether the attendant's switchboard is in the same main-branch office district with the calling party, 90 or not.

In accordance with this invention applied to the system chosen for its elucidation, each telephone line terminates in a line switch, and the latter have common access to a plurality of first selectors. The first selectors have common access to a plurality of second selectors, which latter have common access to a plurality of third selectors. The third selectors have common access to a plurality 95 of connectors, which latter have common access to certain groups of subscribers' lines. In addition to the foregoing, the first selectors have common access to a group of 100 selectors which may be termed special second selectors. The latter have common access to

cess to special trunks, telephones and equipments off certain levels and have common access to the said second selectors off corresponding levels with the said first selectors. In practice, the first level of the first selectors would ordinarily extend to the special second selectors.

Assume, now, that a preliminary digit "1" is sent by the calling subscriber accidentally or directedly before digit "2", for example, is called, in calling a telephone number beginning with digit "2". A trunk of a group of trunks leading from the first level of the first selector to a special second selector will be attained. Then, upon the digit "2" being called, the special second selector seized will attain connection through its second level with the group of trunks extending to second selectors from the second level of the first selectors in common with the second level of the special second selectors. In view of the foregoing, regardless of the initial digit being "1" or "2", the same group of trunks extending to second selectors is attained. That is to say, if a telephone number beginning with digit "2" is called, prefixing digit "1" will not vitiate the call. However, if the first digit "1" is followed by digit "1", the special second selector will select a trunk on its first level. These latter trunks may extend to special office attendants, as, information, wirechief and complaint switchboard, or to telephones. Special second selectors, and also the first selectors, functioning as described have been used heretofore, and are well known.

However, the present invention among other novel features contemplates a companion selector as C in correlation (or adapted to be associated through the agency of a selecting switch) with each special second selector as B, and that the attendant receiving the call can, by automatic control means cause the said companion selector to operate and attain connection with a succeeding (second or special second) second selector or a succeeding special second selector of the group containing selector B which may be thereafter operated under control of the attendant to the end of completing a connection through the exchange apparatus to the wanted telephone essentially as if the calling subscriber himself had controlled the connection automatically from the first selector directly, in lieu of first calling the attendant. The attendant may converse with the wanted subscriber privately or with the calling subscriber also in telephonic relation. Means is provided for releasing the special second selector B co-operating with the first selector A and the apparatus towards the attendant's switchboard, so the links will then be direct from the first selector A to the companion second selector C associated with the

special second selector B and to a second selector (or special second selector not shown), and thence through succeeding switches from the said companion selector C as in a normal connection from a first selector, directed wholly by the calling subscriber.

Where the attendant's switchboard is in a main-branch office district of the exchange, remotely located from the main branch office district containing the calling subscriber, the call may route over trunks reserved exclusively for such service off the first level (or other level or levels) of the special second selectors, or they may route over the regular exchange traffic trunks provided for general switching between subscribers. A form of trunk repeater of my invention is provided enabling the dual use to be enjoyed as will be detailed presently. In instances, a certain number of special trunks, also involving a trunk repeater of my invention, would be provided extending from the various main-branch offices to the attendant's switchboard, and other last-choice trunks, perhaps, used for general switching, reserved for the dual use, would be available when all the special attendant's trunks are busy.

In the accompanying drawings:—

Fig. 1 shows a subscriber's automatic telephone T leading to a pre-selector PS, and the latter is in selective relation to a first selector A. A is in selective relation to second selectors and special second selectors. These elements, in the indicated relation are well known in the art.

Fig. 2 shows a novel special second selector, B.

Fig. 3 shows a novel companion selector to B.

Fig. 4 is a diagrammatic representation of a second selector 2S, third selector 3S, connector CON, and a called line leading to telephone T4. These elements, in the indicated relation, are well known in the art.

Fig. 5 shows a novel trunk repeater.

Fig. 6 shows a novel dual-service trunk repeater.

Fig. 7 comprises a second selector F, a third selector 3S', a connector CON7, and a called telephone T7. These elements, in the indicated relation, are well known in the art.

Fig. 8 shows an attendant's receiving circuit.

Figs. 9, 10, 11 and 12, respectively, show a method of arranging the various figures to form operative circuit relations (as will be described) suitable to elucidate the invention.

Fig. 13 shows a switching cord pair for continuing a connection from the springjack in Fig. 8 to a called manual common battery line H.

Fig. 14 shows a plug-ending connecting

circuit attaching to the right of Fig. 8, and a called manual common battery line H.

Referring to certain of the various figures:—

5 In Fig. 1, T is the usual series type of automatic telephone having a calling device 12 of the general class as shown in British patent to Dicker, No. 29,654 of 1910. The pre-selector PS is of the general class as shown in U. S. patent to Lamb, No. 1,193,160, granted August 1, 1916. The first selector A is of the general class as shown in U. S. patent to Keith and Erickson, No. 815,321, granted March 13, 1906, of course modified in mechanical and circuit details 15 to operate on the well known so-called two-wire principle.

In Fig. 2, special second selector B, is of the same class as A of Fig. 1, of course 20 having novel operative functions, as will appear.

In Fig. 3, selector C, which is companion to selector B, is of the same class as A of Fig. 1, of course, having novel operative 25 function, as will appear.

In Fig. 4, second selector 2S, is similar in detail to selector A. Also, third selector 3S, is similar in detail to selector A. Connector CON, may be assumed similar in detail to the connector H shown in U. S. Patent No. 13,901, reissued April 13, 1915, to Frank Newforth. Pre-selector PS4 is similar in detail to pre-selector PS. Telephone T4 is similar in detail to telephone T.

35 In Fig. 7, second selector F, is similar in detail to selector A. Third selector 3S' is similar in detail to A. Connector CON7 is similar in detail to selector connector CON. Telephone T7 is similar in detail to telephone T.

To simplify the drawings and descriptions, battery and ground are shown as independent sources throughout, wherever applied, but it is to be understood that the 45 system is of the common battery type. In the descriptions, when a circuit is traced to a winding, the opposite terminal of which is shown applied to grounded battery or to ground, the described circuit is to be considered as traced to ground through the winding to battery, or direct to ground as indicated.

The performance of the equipments will be detailed under different assumed operative conditions, bearing in mind that the equipment elements may be variously organized in the assembly of a system.

Referring to the accompanying drawings:—

60 Assume a call from telephone T to telephone T4, the telephone number of which is "31111". The Figs. 1, 2, 3 and 4 are assembled in numerical order as shown in Fig. 9, however, Figs. 5 and 8 not entering 65 into the present assumed call.

Upon the calling subscriber initiating the call by removing the receiver from the switchhook of telephone T the pre-selector PS will function in the well known manner and extend the connection to the first selector A, which latter is assumed to be the first seizable first selector of a group accessible to the pre-selector PS. A circuit exists after the seizure of selector A, from grounded battery, upper winding of control 70 relay 13, armature 14, conductor 15, pre-selector wiper 16, conductor 17, telephone T, conductor 18, pre-selector wiper 19, conductor 20, armature 21, lower winding of relay 15 to ground, relay 13 actuating. Slow-releasing relay 22 is energized through 75 grounded armature 23. Private conductor 24 is grounded through contact 25. Cut-off relay CR is maintained from conductor 24 in the well known manner. 80

Upon the calling subscriber operating the calling device 12 in accordance with the first digit "3" the shaft of selector A (driven by vertical magnet V) will be caused to be raised three vertical steps, its 90 wipers aligning with the third bank level, and then caused to be automatically rotated-in (driven by rotary magnet R). The wipers 26, 27 and 28 will be rotated until they engage and seize the first idle trunk in the 95 well known manner. It will be assumed that the set of bank contacts seized is 29, 30 and 31, being the first set of the level. Relay 32 will actuate in effecting the seizure. Relays 13 and 22 will de-actuate in 100 sequence. A telephonic circuit can now be traced from armature 14, conductor 32, wiper 27, bank contact 30, conductor 33 to grounded battery through the upper winding of a control relay of the second selector 105 2S corresponding to relay 13, and from ground through the lower winding of the said control relay in selector 2S, conductor 401, bank contact 31, wiper 28, conductor 34 to armature 21. Conductor 402 will become grounded from the slow-releasing relay in selector 2S corresponding to 22 which 110 will maintain ground on conductor 24, and therefore relay 32 will be maintained actuated and busy ground will endure on bank 115 contact 29 and its multiples.

Upon operating the calling device 12 in accordance with the second digit "1", second selector 2S will be caused to raise its wipers one step to align with the first level 120 of bank contacts, and automatically rotate-in thereat and seize the first disengaged trunk, which will be assumed is the one leading to third selector 3S.

Upon operating the calling device 12 in 125 accordance with the third digit "1", said third selector 3S will be caused to raise its wipers one step into alignment with the first level of bank contacts and automatically rotate-in thereat and seize the first disengaged 130

trunk which will be assumed to be the one leading to connector CON.

Upon operating the calling device 12 in accordance with the fourth digit "1", the said conductor will be caused to raise its wipers to align with the first level of bank contacts.

Upon operating the calling device 12 in accordance with the fifth (last) digit "1", the wipers of the said connector will be caused to be rotated one step and engage, seize and signal upon the line extending to telephone T4; all in a manner well known. The release of the described established connection upon the calling subscriber restoring his receiver will not be detailed, since the functioning of the concerned elements, which are old in the art, is well known.

20 Assume a call from telephone T to telephone T7, the telephone number of which is "21111". The figures will be assembled as shown in Fig. 11, though Fig. 8 indicated therein has no operative relation in the present assumed call. The call will be initiated in the manner before described, and the calling subscriber will first operate the calling device 12 in accordance with digit "2" in lieu of digit "3", whereupon the selector

25 A will seize the first trunk in the second level in the manner set forth, wipers 26, 27 and 28 seizing bank contacts 35, 36 and 37 respectively. A circuit can now be traced from the calling telephone T to the said contacts 36 and 37 and from said 36, conductor 38, conductor 39, armature 601, contact 602, upper winding of relay 603 to grounded battery, and from ground, lower winding of relay 603, spring 604, armature

30 605, conductor 606, conductor 201 to contact 37. The windings of relay 603 will thus operatively energize in series with the calling telephone T. Slow-releasing relay 607 will actuate due to ground on armature 608.

35 Ground from contact 609 is applied over conductor 610 to conductor 202 and to its multiplied private bank contacts 35, 203 and 301. This will maintain ground on conductor 24, and relay 32 will be maintained actuated as before set forth. Ground from contact 611 is applied over conductor 612 to private bank contact 204 and multiples accessible to special second selectors similar to B. Thus, when repeater E is seized by a first

40 selector, or by a special second selector as B, as will appear, the trunk is incidentally guarded against the other first selectors and special second selectors, not shown. A circuit can now be traced from grounded battery through upper winding of control relay 701, armature 702, conductor 703, conductor 613, contact 614, contact 615, inner winding of relay 616, contact 617, lower winding of relay 618, contact 619, conductor

45 620, conductor 704, armature 705, through

lower winding of relay 701 to ground, relay 701 actuating.

Upon the calling subscriber operating the calling device 12 in accordance with the second digit "1", the control relay 603 will de-actuate and re-actuate one time responsive thereto, opening the described circuit including the windings of relay 701 at contact 619. Slow-releasing relay 622 will actuate incidental to relay 603 de-actuating, 75 due to the closure of a circuit from the winding of said 622, armature 623 to grounded armature 608. At the termination of the period of relay 622 following the re-actuation of relay 603, after calling device 12 80 has returned to normal relay 622 will de-actuate, restoring the traced circuit including the windings of relay 701. Opening the energizing circuit of relay 701 for an instant as described, will cause the vertical magnet 85 V7 to raise the shaft carrying the wipers 706, 707 and 708 to an alignment with the first level, whereupon the rotary magnet R7 will automatically function to rotate the wipers into engagement and seizure of the 90 first bank contacts 709, 710 and 711, respectively, which is assumed to be the first set of idle contacts leading to an accessible third selector 3S'. The functioning of selector F is well known in the art and will therefore not be detailed.

Upon the calling subscriber operating the calling device 12 in accordance with the third digit "1", relay 603 and other elements of repeater E will function as before described, bearing in mind that this time the relay 701 is disassociated due to relay 712 having actuated to effect the stated seizure of selector 3S', and that conductors 703 and 704 have therefore been continued through 100 wipers 707 and 708 and bank contacts 710 and 711 respectively, to a control relay in third selector 3S' similar to and disposed as control relay 701. Thus, the third selector 3S' will be caused to function like 110 selector F functioned as set forth, and the connector CON7 is seized through wipers 713 and 714, disassociating the said control relay in said selector 3S' corresponding to 701. Then, connector CON7 will operate 115 responsive to the two last digits "1-1" in a manner as described in relation to connector CON, and seize and ring upon the line leading to telephone T7, the repeater E functioning as before set forth.

120 The connector CON7 (bearing in mind the cited reference thereto) reverses the battery projected over the leading-in conductors including the inner winding of relay 616. When relay 607 actuates, a circuit from the 125 outer winding of relay 616 to grounded contact 609 is closed. The said outer winding, though energized, is alone insufficient to cause the attraction of its influenced armature. The direction of current traced 130

through the inner winding (before a response from the telephone T7 is such as to tend to neutralize the energization of the outer winding of relay 616. Therefore, 5 when the current projected from the control relay (relay 16 in the said cited patent to Newforth) is reversed consequent to the response of the called telephone, the currents in the inner and outer windings of relay 616 10 will energize cumulatively, effective to attract its influenced armatures. A circuit can now be traced from the winding of relay 624 to grounded contact 625, relay 624 actuating and reversing the leading-in line 15 regulation with respect to the windings of relay 603. Repeaters functioning as specifically set forth with respect to repeater E are well known in the art. However, as will appear presently, there are other functional characteristics and circuit details of said repeater E which are novel and relate to the present invention.

Upon the calling subscriber at telephone T replacing the receiver, relay 603 will 20 energize, opening the circuit including line conductors 613 and 620, and therefore, the connector CON7, selector 3S', and selector F will restore in the well known manner. The foregoing traced calls from subscriber's telephone T to subscribers' telephones T4 and 25 T7 is by way of showing the normal traffic uses of the system involving the present invention.

Assume that in calling telephone T4 from 30 T, a preliminary impulse constituting digit "1" will be introduced. Then, upon initiating the call by removing the receiver from the switchhook of T, first selector A will be seized as before set forth. The introduction 35 of an open impulse constituting digit "1", after the said seizure, by an accidental operation of the switchhook or by a directed manipulation of the calling device 12, will cause the selector A to function as before 40 described, only in this instance it will rotate-in automatically on the first bank level and seize the first set of bank contacts, they being assumed as idle when engaged. 45 Wipers 26, 27 and 28 are thus in engagement with bank contacts 36', 37' and 38', leading to conductors 39', 40 and 41, and conductors 42, 43 and 44 respectively. The latter conductors lead into the novel special second selector B. Attention is here called 50 to the fact that the said selector B, as regards the portion including control relay 210 and the equipments on the right thereof constitutes the same arrangement and circuit detail with relation to conductors 44, 43 and 42 as selector A does as regards conductors 20, 15 and 24 respectively. Relays 55 206, 207 and 208 and associated circuits have functions as will appear, but for the present may be assumed fixed in the circuit disposition shown. Under the latter assumption,

the special second selector B is in detail equivalently similar to selector A. It may be remarked here that special second selectors of the kind shown in A of Fig. 1 (and the equivalent assumed condition of selector B) are old in the art, though its operation will be somewhat detailed to insure the fullest comprehension of the adaptations of the present invention in the system illustrative of it. 75

At this juncture a circuit may be traced from grounded battery through upper winding or relay 210, upper armature of relay 205, armature 211, contact 212, conductor 44, conductor 41, bank contact 37', wiper 27, conductor 32, armature 14 and over the described path through telephone T to armature 21, conductor 34, wiper 28, bank contact 38', conductor 40, conductor 43, contact 213, armature 214, lower armature of relay 205, lower winding of relay 210 to ground, said 80 210 actuating. Slow-releasing relay 215 will actuate due to its winding being grounded through grounded armature 216. A circuit can now be traced from grounded contact 90 217, conductor 42, conductor 39', bank contact 36', wiper 26 to conductor 24, which latter will operate to maintain the pre-selector PS and the first selector A in a manner as before set forth. 95

Bearing in mind that the respective bank contacts of the third level accessible to said selector A and said selector B are in multiple relation, common to the leading-in conductors of second selector 2S, it is manifest 100 that if the first digit "3" of the telephone number "31111" belonging to telephone T4 is now called from calling device 12, special second selector B will be caused to function 105 as set forth in describing the operation of first selector A when digit "3" was called, wherein no preliminary impulse was transmitted. That is to say, the shaft of said selector B will be raised by the vertical magnet V2 so the wipers 218, 219, 220, 221 110 and 222 align with the third bank level, where the wipers are caused to be automatically rotated-in, driven by the rotary magnet R2, until the first idle trunk is encountered and seized. This seized trunk will 115 be assumed to be the first one of the bank level, being the one leading from the set of contacts 223, 224, 225, 226 and 227 respectively. The said seizure, of course, implies 120 that relay 205 will actuate to cause the seizure, and that relays 210 and 215 will restore in sequence. Wipers 219 and 220 have no operative purpose in the present connection. It is apparent in the drawings the bank contacts 223, 226 and 227 are (as stated) in 125 multiple relation with bank contacts 29, 30 and 31, and with conductors 402, 33, and 401 respectively, which latter lead to the leading-in terminals of second selector 2S. So through the agency of selector B an alter- 130

native path from selector A to selector 28 is formulated consequent upon prefixing digit "1" to the first digit "3" of the number of the called telephone. It will be manifest from the disposition of the bank contacts of selectors A and B set forth at the outset that this expedient is correspondingly operative regardless of what (certain) first digit of a telephone number is called. For example, if digit "1" were prefixed when calling telephone number "21111," being telephone T7, the special second selector B would attain the same outgoing trunk leading through repeater E to second selector F, off the second bank level of said selector B, as if the digit "1" were not set and that selector A responded primarily to digit "2".

In commercial telephone exchange systems the employment of the first level of the first selectors as it relates to general subscribers' numbers is not found satisfactory, due to the fact that preliminary or false impulses constituting digit "1" are often introduced, either by carelessly removing the receiver from the switch-hook and thereby effecting an open impulse, or through introducing the said impulse otherwise. The nominal capacity of the exchange system is thus reduced one operative level, so far as general subscribers are concerned. It is found convenient in instances to employ the said first level in gaining connection with "company" or exchange attendants' equipments, and, as has been set forth, to divert a call which has become vitiated through a preliminary impulse, back into its normal selective route towards the wanted telephone line.

It will be assumed for the present that the information department in the exampled system is reached by calling telephone number "14". Attention is directed to Fig. 9, which shows the relation of the various figures in the circuit assembly about to be described.

To avoid involving the drawings too greatly, the lower level of bank contacts shown accessible to selector B (and other similar selectors of the group) is, in the description about to be entered into relating to the call to the information department is assumed to be the fourth level, rather than the first level as it is shown in the drawing. Fig. 8 is for the present assumed as constituting the essential equipment elements at the switchboard of the said information department.

The calling subscriber at telephone T will initiate the call and attain the first selector A by removing the receiver, and thereafter attain the special second selector B by operating the calling device 12 in accordance with digit "1", as before detailed. Upon operating the calling device 12 in accordance with the second digit "4,"

the selector B will function in the manner, generally, as before described in relation to digit "3", thus attaining the fourth bank level and there automatically rotating the wipers 218, 219, 220, 221 and 222, selecting the first idle trunk, which will be assumed as being the one leading from the first set of bank contacts 204, 232, 233, 234 and 235, of course, bearing in mind that for the present convenience of illustration the said fourth level is shown as the first level bank contact set.

A circuit can now be traced from grounded battery through upper winding of relay 501, conductor 502, bank contact 234, wiper 221, conductor 236, armature 237, contact 212, over the described path including telephone T to contact 213, contact 238, conductor 240, wiper 222, bank contact 235, conductor 503, lower winding of relay 501 to ground, relay 501 actuating. Fig. 5 being preferably in the same exchange main-branch office district as selectors B and A and telephone T affords transmitter excitation battery to telephone T of ample strength.

An operative circuit can now be traced from the winding of slow-releasing relay 504 to grounded armature 505. Ground on contact 506 will be applied over conductor 507 to bank contact 204 and its multiples, guarding the repeater D against seizure by other selectors similar to selector B in common access to it, and it also serves to maintain selectors B and A and preselector PS in a manner as has been set forth. A circuit can also be traced from grounded armature 509, winding of relay 510, conductor 511, conductor 801, retardation coil 802, winding of relay 803 to grounded battery. Relay 510 is marginally adjusted not to operate with the resistance value of said 802 in circuit as traced, but will operate if said 802 is short-circuited. Relay 803 will operate under either said condition relating to retardation coil 802. Relay 803 being thus caused to be actuated, calling lamp 804 will have battery derived through it, armature 805 to grounded armature 806.

The attendant at G upon observing the glowing of lamp 804 will respond by manipulating key 807.

The telephonic circuit from telephone T to bank contacts 234 and 235 has been traced and the said circuit is now continued over conductor 502, condenser 512, conductor 511, conductor 801, spring 808, spring 809, conductor 810, through operator's set T8, conductor 811, spring 812, spring 813, conductor 814, conductor 513, condenser 514, conductor 503 to bank contact 235. The subscriber at telephone T is thus in telephonic relation with the attendant at G.

Incidental to the manipulation of key 807 an operative circuit is closed from the winding of relay 815, make-before-break spring 130

816, to grounded spring 817. Armature 806, attracting, opens the traced energizing circuit for lamp 804 and closes a circuit to ground from lamp 818. Thus, upon the manipulation of key 807 lamp 804 is extinguished and lamp 818 is caused to glow. A locking circuit for relay 815 is closed from its winding, spring 816, armature 819, to grounded contact 820. Relay 803 is held actuated dependent upon armature 509 of relay 501, and the latter relay is, in turn, held actuated dependent upon the maintained closure of the circuit including telephone T; also upon the dis-association of the wipers 221 and 222 from bank contacts 234 and 235 respectively. So the lamp 818 will glow until the selector B releases from its seized bank contacts, or the calling subscriber replaces the receiver.

It may be stated here that under the condition wherein lamp 818 is glowing and lamp 804 is extinguished the calling subscriber can cause the said 818 to extinguish and lamp 804 to re-glow to attract the attendant. This is done by manipulating the calling device 12 (or by flashing the switch-hook) so as to open the energizing circuit of relay 501 for a brief period and thereby cause its armature 509 to retract, and in turn open the energizing circuit of relay 803. Relay 803 will de-actuate momentarily and re-attract upon the re-attraction of armature 509 when the circuit including the windings of relay 501 is re-established.

Since relay 815 is maintained locked through contact 820, it (815) will become unlocked and lamp 818 will extinguish, and lamp 804 will re-glow. Were the armature 509 and its co-operating contact transferred to relay 504, the circuit operation described would not be altered, only, now, that as relay 504 will sustain over current lapses of the period effectuated by the calling device 12 wherein armature 505 retracts responsive thereto, no re-glowing of lamp 804 as set forth can ensue unless the call is effaced and re-established.

It will now be assumed that the calling subscriber is enquiring for the telephone number of telephone T4. The information attendant (at G) informs the subscriber the number is "31111," but in order to save time and effort to the calling subscriber, that the connection will be given him and for him to hold the receiver, whereupon the attendant at G will manipulate the key cam 821 to restore key 807 and operate key 822.

Springs 823 and 824 short-circuit the retardation coil 802, which function will augment the current flow in the traced path, including relay 510, to its operating value, whereupon ground from contact 515 will be applied over conductor 516 to bank contact 233, wiper 220, armature 241, conductor 242, to the winding of relay 302, causing said 302 to actuate. An operative circuit can now be traced from grounded contact 303, conductor 305 to the winding of slow-releasing relay 208. Also, an operative circuit can now be traced from grounded armature 306, conductor 307 to the winding of relay 206. Bearing in mind that conductor 42 now receives ground from contact 506, a locking circuit exists from the winding of relay 206 through its lower armature 75 to said conductor 42, maintaining relay 206.

It will be observed that at this juncture retardation coil 250 (through inside make-before-break springs of relay 208) is in bridge of armatures 211 and 214, and therefore, included in series with the windings of relay 501, maintaining said 501. An operative circuit can also be traced from grounded battery through the upper winding of control relay 308, armature 311, armature 214, 80 winding of retardation coil 250, armature 211, contact 245, conductor 246, armature 315 to ground through the lower winding of relay 308. Also, an operative circuit can be traced from grounded battery through 90 the lower winding of relay 316, conductor 317, armature 247, conductor 44, through the traced path including telephone T to conductor 43, armature 248, conductor 249, to ground through the upper winding of relay 316. The object of relay 316 will appear presently.

A circuit path can now be traced from the winding of relay 207, conductor 255, armature 320, conductor 321, armature 257, 100 wiper 219, bank contact 232, conductor 258, conductor 520, conductor 513, conductor 814, springs 830 and 831, conductor 832 to free dial spring 833. A conductor 835 is legged off conductor 832. It branches to key spring 105 836 and to armature 837. The purpose of said 836 and 837 will appear presently.

The information attendant at G will now proceed to operate the calling device CD in accordance with the successive digits of the 110 telephone number ("31111") of the wanted telephone T4. Upon the operation of the calling device CD in accordance with the first digit "3," grounded spring 838 will be applied to spring 833 for three brief periods, 115 thus closing the traced circuit path including the winding of relay 207 correspondingly.

It follows, that consequent to the actuation of relay 207 the traced circuit path including the windings of relay 308, will be opened three times. Bearing in mind that relay 302 is actuated (and therefore armature 322 is in engagement with its co-operating contact) and that the armature 323 120 and its co-operating contact are auxiliary and have no direct operative purpose in selector C, it will be manifest that the circuits of said C are similar to those of first selector A, and therefore, the operation of selector 125 130

tor C responsive to the control relay 308 is well known and need not be detailed in imparting a clear understanding of said C.

So in view of the last foregoing statement, it will be sufficient to say that upon relay 308 de-actuating and re-actuating three times because of the stated opening of its energizing circuit, that the wipers 325, 326 and 327 will be raised three vertical 10 steps and align with the third level of bank contacts, through the agency of vertical magnet V3, and then caused to be automatically driven rotarily through the agency of the rotary magnet R3. The said rotary 15 functioning will proceed until an idle trunk is encountered, when it will seize its terminating bank contacts, relay 330 actuating in the well known manner, whereupon relay 308 and slow-releasing relay 331 will de-actuate in sequence; also in a manner well 20 known. It will be assumed that the set of bank contacts seized is the first set of the level, 335, 336 and 337 leading to conductors 402, 401 and 33 respectively. The said latter 25 conductors have been described as leading to the leading-in conductors of second selector 2S.

Upon the said calling device CD being next operated in accordance with the second digit "1," said 2S will function in the manner as before set forth and select and seize the trunk leading to the third selector 3S. Upon the said CD being next operated in accordance with the third digit "1," said 3S will function in the manner as here-to 30 fore set forth, and select and seize the trunk leading to the connector CON. Upon the said CD being next operated in accordance with the fourth digit "1," said CON will operate, and seize and ring upon the line 35 leading to telephone T4 in the manner as hereinbefore set forth.

It will be assumed that at this juncture the wanted party has not yet responded before the attendant at G restores the key cam 45 821 to normal, the forwarding of the call having been completed. Relay 510 will de-actuate due to the short-circuit around the retardation 802 having been thus removed. It follows that relay 302 will de-actuate and also its dependent relay 208, relay 206 remaining locked to conductor 42. After the period of slow-releasing relay 208, an operative circuit can be traced from grounded 50 contact 340, lower armature of relay 208, conductor 260, armature 323, conductor 343 to the winding of the release magnet Re2, causing selector B to be restored, whereupon relay 501 and its dependent relay 504 55 will de-actuate in sequence, and relay 803 will de-actuate because of the retraction of armature 509. The relay 815 will have its locking circuit opened at contact 820, so lamp 818 will extinguish, indexing the condition. Due to conductor 402 being now

also grounded from the connector CON, conductor 42 will not be subjected to a ground lapse, because of armature 506 retracting, and therefore, relay 206 will remain actuated and relay 210 dis-associated. 70 The telephonic circuit traced from telephone T to conductors 43 and 44 and the telephonic conductors traced from telephone T4 to conductors 312 and 246 are joined through contact 213 and armature 214; and 75 contact 212, armature 211 and contact 245; respectively, and, furthermore, it is clear of operative and affecting connections from the telephone T to the connector CON. Selector B having been released, the repeater 80 D and its leading-in trunk is now available to subsequent calls.

Upon the calling subscriber replacing the receiver at telephone T the connector CON will be released and ground will be removed 85 from conductor 42 in the well known manner, and the said connector will restore and relays 330 and 32 will de-actuate because thereof. Release magnet Re3 will restore selector C due to its energizing circuit becoming similarly closed.

It has been stated and set forth that while the described impulsion was ensuing, the calling subscriber is cut off from the wipers of selector B and terminated in the windings of relay 316. The purpose of this is as follows: Upon relay 208 actuating, no great disturbance due to a lapse of current is heard through the receiver at telephone T, because no lapse of excitation battery is 95 entailed incident to deriving current through the windings of relay 316 in lieu of through the windings of relay 210. The relay 316 also serves to release the connection at any instant under control of the calling subscriber at telephone T, regardless of the fact the attendant at G may have taken control and may be forwarding the call as described. For example, should the calling subscriber at telephone T replace the receiver while 100 relay 208 is actuated and key 822 is operated, as set forth, relay 316 will de-energize and de-actuate. An operative circuit will then ensue from release magnet Re2, conductor 343, conductor 344, armature 345, 105 conductor 346, armature 259, conductor 341, to grounded contact 340. The selector B will thus restore, whereupon the trunk leading to the repeater D will be disengaged and lamp 818 will extinguish, indexing the condition. 110

Assume that before key 822 is operated and while key 807 is operated as set forth hereinbefore, the calling subscriber at telephone T replaces the receiver. Under this 115 condition relay 205 is the only relay operated in selector B, and all relays in selector C are normal. Relay 501 is energized over a circuit including telephone T under this condition. Therefore, when the receiver at 120 125 130

telephone T is re-placed, relay 501 will de-actuate and remove the holding ground from the winding of relay 205, causing it to de-actuate and complete an operative circuit 5 from grounded armature 216 armature 260, armature 261, spring 262, to release magnet Re2, causing the restoration of selector B since relay 501 is de-actuated, its dependent relay 803 will de-actuate, and lamp 804 will 10 extinguish. It will appear presently that were alternative answering key 840 operated (cam 821 being normal) and the calling subscriber at telephone T replaces the receiver, the same functioning of selector B 15 will take place as detailed under the condition of the said restoration with key 822 operated, due to the fact the same relays in selectors B and C (not considering relay 207 controlled by calling device CD) are 20 operated.

In view of the last foregoing statements, the function of key 840 will be discussed here. It will appear presently that the function of said key 840 is different depending 25 upon whether it is operated after key 822 is operated (as it ordinarily would be) or if said key 840 is operated when said key 822 has remained at normal. If key 807 has remained at normal since calling lamp 804 30 became glowing, upon the operation of key 840, an operative circuit will become completed from the winding of relay 815, spring 816, spring 841 to grounded spring 842, causing relay 815 to extinguish lamp 804 35 and light lamp 818 in the manner before described in reference to key 807. Also, retardation coil 802 will be short-circuited through springs 843 and 844, thus augmenting the current strength in winding of relay 40 510 to its operative value, whereupon the relays 302, 206 and 208 will actuate as before set forth in relation to key 822, wherein the calling telephone T is dis-associated by relay 208 and applied to relay 316. However, 45 the key 840 would not, in practice, be operated until after key 807 and key 822 have been operated and the wanted telephone T4 has been signaled. Under this condition, key 807 having been operated, 50 relay 206 is locked actuated as described. Then, when the key 840 is thereafter operated and retardation coil 802 is thereby short-circuited, relay 510 actuates and in turn causes relays 302 and 208 to actuate 55 (relay 206 being already locked actuated). A telephonic circuit can now be traced from operator's set T8, conductor 810, key spring 845, spring 844, conductor 801, conductor 511, condenser 512, conductor 502, bank contact 234, wiper 221, conductor 236, armature 237, armature 211, contact 245, conductor 246, armature 315, conductor 348, wiper 327, bank contact 337, conductor 401, through the selector 2S, selector 3S, connector CON, telephone T4, back through

connector CON, selector 3S, selector 2S, conductor 33, bank contact 336, wiper 326, conductor 349, armature 311, conductor 312, armature 214, contact 238, conductor 240, wiper 222, bank contact 235, conductor 503, 70 condenser 514, conductor 513, conductor 814, spring 846, spring 847, conductor 811, to operator's set T8. It will be noted that retardation coil 250 is in bridge of the telephonic limbs attached to armature 211 and 214. Also, that the calling telephone T is disassociated. Manifestly, this permits the attendant at G to converse with the called subscriber at telephone T4 secretly so far as the subscriber at telephone T is concerned. 80 Restoring key 840 allows relays 510, 302 and 208 to de-actuate and re-establish the previously traced telephonic path between the telephone T and the telephone T4. Incidental to the restoration of key 840 (with 85 regard to the state of relay 208 because thereof) a circuit can be traced from grounded contact 340, conductor 341, armature 259, conductor 260, armature 323, conductor 343, to the winding of release magnet Re2, causing it to actuate and restore selector B, together with the consequent functioning of said D and G as set forth. Thus, when the attendant at G restores key 840, the trunk to said G is freed consequent 90 thereto. If it is desired to listen-in on the conversation, after the establishment of the telephonic circuit between T and T4 (by restoring key 840), without (of course) restoring selector B as set forth, key 807 is 95 operated before key 840 is released. Key 807 now closes a circuit from grounded spring 848, spring 849, winding of retardation coil 850, conductor 814, conductor 513, conductor 520, conductor 258, bank contact 232, wiper 219, armature 257, (relay 206 being locked actuated), conductor 321, armature 320 to the winding of relay 351, said 100 351 actuating. Grounded contact 340 being now disassociated, the traced path 105 from said 340 to the winding of release magnet Re2 is opened, so when relay 208 de-actuates in re-establishing the telephonic connection between T and T4, no release of the selector B can take place, and the previously traced telephonic path through springs 809 and 812 will now include the conductors 246 and 312 leading to the telephone T4 due to armature 211 and 214 of relay 206 being attracted. However, upon 110 restoring key 807, the described energizing circuit of relay 351 is opened, causing the armature of said 351 to retract against grounded contact 340 and thereby re-establish the energizing circuit of release magnet Re2, whereupon the selector B is 115 restored as before set forth.

It will be recalled that while the attendant at G was forwarding the call with key 822 operated, relay 208 was operated and 120 125 130

the calling subscriber's line was applied to the windings of relay 316. Also, relay 207 actuated and de-actuated in effectuating each impulse effective to de-energize relay 308. For each attraction of armature 267 of relay 207, ground through resistance 266 is applied to conductor 249 and it thereby short-circuits the upper winding of relay 316 and augments the current flow traversing the calling telephone T for the period of the impulse from the calling device CD. The fluctuations of current produce disturbances audible to the calling subscriber, indexing the fact the call is being forwarded, and also the number of impulses in the series of impulses controlling it.

From the foregoing, when the call is completed from the called telephone T to the called telephone T4 through the selector 20 C, relay 206 is the only relay in selector B in an operated condition, and relay 330 is the only relay in selector C in an operated condition.

Assume that after the attendant at G has started the forwarding of the call described, through the agency of key 822 and the calling device CD, it becomes desirous for some reason to negate the call impulses sent, perhaps because of an error on the part of the attendant in operating the calling device CD. This restoring of the selector C and any successive switch thereto, is accomplished by operating the key spring 836 to engage its grounded co-operating contact and so maintaining it for a period sufficient to cause the slow-releasing relay (as 331 of C) of the remotest switch towards the called line to de-actuate and cause the circuit of the release magnet (as Re3) to be closed in a manner well known. The grounding of conductor 835 from spring 836 will hold relay 207 actuated beyond the critical period of the slow-releasing relay last referred to. This, however, will not cause the restoration of selector B, so the call can be thereafter re-forwarded normally by operating the calling device CD.

At the upper right-hand corner of Fig. 8 two relays, and designations thereto, are shown as they are disposed in the pending application of Herbert M. Friendly (the present applicant) and Frank L. Fisher, co-inventors, Serial No. 302,807, filed June 9, 1919, covering an impulse transmitting device. Conductor 835 extends to armature 837. The armature 837, contact 852, armature 853 and grounded contact 854 are added in adapting the said referred-to application last mentioned to the present invention.

Assume that the said connection is established from telephone T to telephone T4 by way of selector C and the selector B has been restored as set forth. If the calling subscriber replaces his receiver the conductor 402 will become ungrounded under control

of the connector CON in a well known manner. Relays 330 and 206 will de-actuate as well as other release-controlling relays attached to conductor 42 in selector A and pre-selector PS. A circuit to operate the release magnet Re3 to restore the selector C will be established in the well known manner from grounded armature 355, armature 356, armature 357, spring 358. The selectors 2S and 3S will restore in a well known manner as described in relation to C, and the connector CON will restore in a well known manner as set forth in the cited patent to Newforth.

It has been set forth in the foregoing descriptions that upon the selector B attaining connection with the trunk including repeater D, that relay 501 actuated, and also supplied energizing current to the telephone T, relays 13 and 210 being dis-associated. Also, that relay 504, dependent upon relay 501, controlled the maintenance of selector B, selector A and pre-selector PS, so, if the subscriber at T replaces his receiver, relay 501 will de-actuate, followed by relay 504, whereupon said B, A and PS will restore, bearing in mind, of course, that relays 803, 815 and lamps 804 and 818 are dependent upon relay 501. The release of said B, A and PS is thus under the control of the calling subscriber under all conditions, excepting the condition set forth wherein key 807 is operated after key 822, or key 840 has been operated and relay 351 is operated, controlled by said 807, relay 206 being locked actuated and relays 302 and 208 are actuated.

Under certain traffic conditions or methods of operation it is desirable to take the last foregoing mentioned control from the calling subscriber and reserve it to the attendant at G. In accordance with incorporating such functions, switch-arms 521, 522 and 359 are introduced to permit of the functions described in relation to said G, D, C, B, A and PS. Switch-arms 521 and 522 are closed and switch-arm 359 is opened. It is manifest that the operative purpose of conductor 344 as set forth is thus negated by the opening of switch-arm 359. The relay 510 will remain actuated, regardless of the condition of relay 501, as long as key 822 (or key 840) is in its operated position. That is to say, regardless of the fact the calling subscriber replaces the receiver, there will be no ground lapse on conductor 42, and, therefore, no release of selector B or selector C can take place and the connection will be locked, to be unlocked only at the will of the attendant at G. This function would be useful, for example, where the origin of certain calls is desired, the connection being maintained to permit of tracing by office attendants.

It will be recalled that in the last assumption

tion, the lowermost bank level was assumed to be the fourth bank level. In the condition about to be set forth, it will be assumed as the fifth level. A call will be traced in view 5 of this from the calling telephone T to the complaint department. The attendant at the complaint department will then transfer or forward the connection to telephone T4 as was done from the information department detailed before. The telephone number of the complaint department is "153." The figures will be assembled as in Fig. 10.

The arrangement shown in Fig. 10 is similar to that in Fig. 9 described, excepting 15 that a selector F is introduced and, therefore, an extra digit is required. After the connection is established from telephone T to the attendant's circuit G, as before set forth, the electrical circuits are the same as 20 described in relation to Fig. 9, bearing in mind, of course, that an extra link selector (F) free of affecting attachments, is intermediate of selectors D and G.

The trunk leading to selector D will be at- 25 tained by the calling subscriber at telephone T as before, excepting that digits "1-5" will be called in place of "1-4," in view of the trunk leading to selector D (now assumed) terminating in the fifth level accessible to selector B and other selectors of its 30 group. After the trunk leading to selector D has been seized and relays 501 and 504 have actuated in the manner before described, an operative circuit can be traced from grounded armature 509, winding of relay 510, conductor 511, conductor 703, armature 702, upper winding of relay 701 to grounded battery. The lower winding of control relay 701 is un-energized.

40 If, now, the calling subscriber at telephone T manipulates the calling device 12 in accordance with the third digit "3," the relay 501 will be correspondingly de-energized and re-energized, since its windings are included in the circuit including the calling device 12 as has been traced hereinbefore. Relay 504 will maintain over the current lapses due to the retractions of armature 505.

The selector F will function as before set 50 forth, responsive to the retractions of relay 701, resultant in the present instance from the retractions of armature 509, and cause the wipers 706, 707 and 708 to be raised three steps to align with the third bank level, and 55 there rotate automatically until an idle trunk line is found and seized through relay 712 actuating. It will be assumed the trunk line seized is the one leading to the first set of bank contacts, and, therefore, wipers 706, 707 and 708 are resting on bank contacts 721, 722, and 723 leading to conductors 724, 725 and 726 respectively. Conductors 725 and 60 726 attach to conductors 801 and 814 respectively.

In this connection it will be noted that 65 when selector F seizes bank contact set 721, 722 and 723 and relay 803 actuates as set forth, a holding or maintaining ground (also serving as a busy guard) is applied from grounded contact 820, conductor 724 70 to bank contact 721. Furthermore, the maintenance of this ground condition on conductor 724 is dependent upon relay 501, so should the calling subscriber at telephone T replace the receiver, and thereby cause relay 501 to de-actuate as has been set forth, the ground maintaining relay 712 actuated will be removed by reason of the retraction of the armature from grounded contact 820. An operative circuit will then be closed from 75 grounded armature 731, armature 732, armature 733, spring 734 to the winding of release magnet Re7, causing the restoration of selector F.

It is manifest, now, that conductors 511 and 513 are in telephonic continuity with conductors 801 and 814 respectively, and that the link selector F intermediate between 80 selectors D and G is conductive only and does not include legs or bridges. In view 90 of the foregoing it is clear that the same equivalent circuit condition exists as regards said A, B, C, D and G, with selector F introduced, as set forth where it (F) was not included, and therefore, the operation of the 95 selectors A, B, C, 2S, 3S, connector CON and repeater D in effecting a connection from telephone T to telephone T4 controlled from attendant's circuit G need not be re-detailed. It is, of course, understood that an exchange 100 system would generally include a plurality of independent circuit links as said A, B, C, D, 2S, 3S, CON, adapted to be variously combined as set forth and that they would 105 be so disposed as to enable a plurality of calling subscribers to simultaneously gain various attendant employes of the operating company, or in fact private attendants located on the premises of subscribers.

Where a selector as F terminates a trunk 110 leading from a repeater D as set forth, a third selector, as 3S', would not be connected from its bank contact sets, though, of course, it would be feasible to connect them thus.

Referring again to Fig. 11 for the assembly of figures as organized in the relation about to be described, wherein a call is made from telephone T to the wirechief's department at attendant's circuit G, and the call 115 is then transferred or forwarded to telephone T4 under control of the attendant at said G. The general object and the functioning in this switching operation is the same as that last described in reference to the assembly of figures as shown in Fig. 9. In this instance the trunk seized will 120 include a repeater E, (in lieu of repeater D which could be substituted for E), the trunk 125

being an alternative dual service trunk as herein described, seized by selector A in the second bank level.

The telephone calling number of the wirechief's department is "113". It will appear presently that repeater E involves not only certain elements of repeaters as are well known in the art as applied to general inter-subscriber traffic, but it also includes elements involved in repeater D, also described herein as a supplemental capacity. That is to say, the repeater E of my invention is a composite repeater, in that it serves two distinct uses of its containing trunk.

In the previous descriptions involving repeater E the selector A attains the trunk including it resultant to the calling of the first digit "2", and in fact, it would attain it, in view of the descriptions, were digits "1-2" called. In the latter case, calling digit "1" will attain selector B. Then, upon digit "2" being called, the wipers of selector B will be raised to align with the second level of bank contacts and there automatically rotate-in. Its wipers 218, 221 and 222 will seize the first disengaged trunk. The trunk leading to repeater E will be assumed, as before, extending from conductors 202, 201 and 38, but which are now reached by selector B through bank contacts 203, 275 and 276 respectively.

The operation of the repeater E in the trunk intermediate of leading-in conductors 202, 201 and 38, and selector F in the exampled call from telephone T to telephone T7 is controlled solely by the calling subscriber at T as has been clearly set forth. The operation of the said repeater E wherein the calling subscriber at telephone T first calls the wirechief at G and then is connected from T by direct route by agencies controlled by the wirechief at G to telephone T4 is as follows: The calling subscriber at telephone T will initiate the call as before set forth and thereafter manipulate the calling device 12 in accordance with digit "1" and, as before set forth, attain connection with special second selector B. Then, upon dialing the second digit "1" the selector B will function as before set forth, this time, however, raising its said wipers to align with the first bank level as drawn, and there rotate-in automatically until an idle trunk is found. This trunk will be assumed the one leading from the first set of bank contacts 204, 232, 233, 234 and 235. A circuit can now be traced from grounded battery, upper winding of relay 630, contact 631, conductor 632, bank contact 234, wiper 221, and over the before traced path through telephone T, wiper 222, bank contact 235, conductor 635, armature 636, lower winding of relay 630 to ground, said 630 actuating.

An operative circuit is now closed from the winding of slow-releasing relay 638 to

grounded armature 639. Grounded armature 640 is applied to conductor 610 and to bank contact 203, guarding the repeater E against seizure on the second level through bank contacts 203, 275 and 276 and multiples thereof accessible to first selectors (as A) and special second selectors, as B and C. Grounded armature 641 is applied to conductor 612, which is conducted to bank contact 204, wiper 218 to conductor 241, thus sustaining B, A and PS as set forth before, and guarding the set of bank contacts concerned from seizure from accessible selectors similarly related as are A, B and C. A circuit can be traced from grounded armature 643, winding of relay 644, conductor 645, conductor 613, conductor 703, armature 702, through upper winding of relay 701 to grounded battery, causing relay 701 to actuate, but due to the marginal characteristic of relay 644 it will not energize with sufficient density with the said winding of relay 701 included to attract its armatures.

Armatures 601 and 605 being attracted, the windings of relay 603 are dis-associated; the latter windings being those of the control relay of the repeater, so far as normal exchange inter-subscriber traffic is concerned in descriptions detailed hereinbefore. In this connection when armatures 631 and 636 are attracted as set forth hereinbefore, the control relay 630 is dis-associated. So if the repeater E is seized from either the first or the second level of selector B, the internal circuits are incidentally adapted to have specific functions peculiar to and dependent upon the level seized. That is to say, if the repeater E is seized from one level (the second in this instance) the repeater E will have effective circuits and functions essentially as well known trunk repeaters used for general inter-subscriber traffic between main-branch offices, and if the repeater E is seized from another level (the first in this instance) the repeater E will have effective circuits and functions essentially as the repeater D of my invention.

The functioning of repeater E has been detailed wherein it co-operated with selector F in attaining connection with telephone T7. Also, the functioning of the repeater D has been detailed wherein it co-operated with selector F. In view of this, it is considered unnecessary to detail the operation of the equipments in the attendant's circuit G and the functioning of the relays 644, 638 and 630 (corresponding to relays 510, 504 and 501 respectively in repeater D) with relation to the forwarding of the call from telephone T to telephone T⁴ and other operative functions controlled from the attendant's circuit G, fully described with relation to Figs. 9 and 10.

The switch-arms 650 and 651 correspond to and have the same operative functions

and purposes as switch-arms 521 and 522 respectively. So, in fact, the repeater E is to all intents and purposes repeater D when seized from the first bank level.

5 In this connection statements made at the outset will prompt an understanding that the trunk containing repeater E is one of a number of subscriber inter-switching trunks connecting one main-branch office 10 with another, and which trunks are adapted to be selected in calling attendant's circuit G when all trunks, such as contain repeaters of the type of repeater D, are busy. Thus, while trunks containing repeaters as 15 E would normally be reserved for general inter-subscriber switching, they are nevertheless automatically convertible to the special uses of the trunks containing repeaters as repeater D. It follows that there would 20 ordinarily be a considerable percentage of trunks used for general inter-subscriber switching containing repeaters with circuits essentially as in repeater E, but with the 25 relays 644, 638 and 630 and interlinked circuits omitted, and, they would, therefore, be of a well known type.

In foregoing descriptions wherein a call is forwarded under control of attendant's circuit G through the agency of companion 30 special second selector C, the wanted telephone was in each instance a subscriber's telephone. It is manifest that since the special second selectors as B and the companion special second selectors as C are 35 commonly accessible to the same trunks, the transferring or forwarding may be to other attendants' switchboards, or even over another trunk of a group to the same attendant's switchboard, for it is to be understood 40 that a plurality of attendant's circuit equipments as G would ordinarily be provided at each attendant's switchboard.

Assume, for example, that a call is to be 45 transferred by the information attendant to the wirechief's switchboard. Bearing in mind previous descriptions, the call will route from calling telephone T through said A, B and D (or E) to the information switchboard, (G). Then, selector C will 50 complete a connection to an accessible special second selector which is a duplicate of selector B, and to the wirechief's switchboard (G) from said duplicate of selector B through a repeater like E (or D) and a selector F. The wirechief can then 55 forward the connection through a companion selector to said duplicate of selector B and which is like selector C, toward selector 2S, in extending the call towards telephone T4, for example. In this case, the connection 60 to telephone T4 would involve selectors A, B, C, a duplicate of selector B and a duplicate of selector C, selectors 2S, 3S and connector CON. Of course, other switching

combinations may be interlinked in the 65 same general manner as that exemplified.

In the descriptions hereinbefore, calls completed from an attendant's switchboard circuit equipment G was effectuated by 70 causing the auxiliary special second selector C to be operatively introduced into the circuits and then forwarded therefrom, and thereafter releasing the connection in the direction of the attendant's circuit equipment G, back to and including special second selector B. In instances, such as where 75 lines to manual subscribers are manually accessible to the attendant it is desirable to effect direct connections through flexible means, such as by cord and plug. Such a 80 plan of operation as referred to here would be adopted where an exchange system comprises a plurality of main branch offices, for example, and that one or more of the said offices is operated as a subscriber controlled 85 automatic office and that one or more of the said offices is operated as a manually switched office. Means, such as contemplated in the present invention and described would permit the subscribers in the 90 automatic office or offices to call an operator, which operator could extend the connection to accessible manual lines through the agency of manual switching means or to automatic office lines by remote control 95 means.

Refer now to Fig. 12 for the arrangement of figures to show such a circuit condition as last referred to. Assume that after the lamp 804 glows and is responded to through key 807 the wanted telephone is disclosed 100 to be T12. Plug 101 is inserted into spring-jack 102. Bearing in mind that relay 803 is actuated and that conductor 724 is, therefore, grounded and relay 103 is actuated because thereof, when plug 101 is raised from its plug-seat switch 104 a circuit can be traced from grounded contact 105, conductor 106, armature 107, lamp 108 to grounded battery, the lamp 108 glowing. The self-restoring key 120 will be briefly depressed, applying ringing current from the source 121 to operate signal device 122 in telephone 110 T12. Upon a response from the subscriber at telephone T12 a circuit can be traced from grounded battery, upper winding of relay 123, conductor 864, springs of key 120, tip 124 of plug 101, tip spring of spring-jack 102, conductor 125, telephone T12, conductor 126, ring spring of springjack 102, ring 127 of plug 101, conductor 865, lower winding of relay 123 to ground, relay 123 actuating. Transmission battery is supplied 120 through the windings of relay 123 over the line H and including the series common battery type telephone T12. The telephonic path from the calling telephone T to conductors 801 and 814 is continued through 125

condensers 861 and 862 to conductors 864 and 865 respectively, so the said calling subscriber is in telephonic communication with the called subscriber at telephone T12.

5 Assume that a conversation is held between the said calling and called subscribers and that the said called subscriber replaces his receiver first. Relay 123 will de-actuate resultant therefrom, and lamp 108 will glow 10 because of a ground path being completed from it through armature 107, conductor 106 to grounded contact 105. This being the disconnect signal, the attendant will withdraw the plug 101 and replace it so it will 15 rest normally in its plug-seat switch 104, disassociating grounded contact 105 and extinguishing lamp 108. Assume that the said calling subscriber replaced his receiver first. Then relay 803 will de-actuate resultant 20 therefrom, because the circuits involved in the attendant's circuit G will have been released in the manner hereinbefore set forth (regardless of whether selector F or repeater D or repeater E is directly co-operating 25 with said G as described hereinbefore), so ground will be removed from conductor 724, causing relay 103 to de-actuate (relay 123 remaining actuated). A circuit can now be traced from grounded contact 105, conductor 106, armature 128, lamp 129 to 30 grounded battery, lamp 129 glowing. This glowing will be a clearing signal indexing the condition, so plug 101 may be withdrawn, or it may be left in the springjack 35 102 until the disconnect signal is given by the said called subscriber as before set forth.

An alternative method of effecting the last foregoing connection is through the agency of the switching cord-pair Fig. 13. Plug 161 40 is lifted from its plug-seat switch 162 and inserted into springjack 863. This extends the traced telephonic patch conductors 864 and 865 from spring 866, tip 160 of plug 161, conductor 163, springs of ringing key 45 164 to tip 165 of plug 166, and from spring 867, ring conductor 167 of plug 161, conductor 168, springs of ringing key 164 to ring 169 of plug 166. An operative circuit can now be traced from grounded contact 50 820, conductor 724, sleeve 866 of springjack 863, conductor 170 of plug 161 to winding of relay 171. Plug 166 is now inserted into springjack 102. A circuit can be traced from grounded sleeve 172 of springjack 102, sleeve 55 173 of plug 166, armature 174, lamp 175 to grounded battery, said 175 glowing. Self-restoring key 164 is depressed for a brief interval, applying ringing current from source 176 to operate signal device 122 to 60 telephone T12. Upon a response from the subscriber at telephone T12, a circuit can be traced from grounded battery, upper winding of relay 177, conductor 163, spring of key 164, tip 165 of plug 166, tip of 65 springjack 102, conductor 125, telephone

T12, conductor 126, ring spring of springjack 102, ring 169 of plug 166, conductor 168, lower winding of relay 177 to ground, said 177 actuating and lamp 175 extinguishing. Transmission battery is supplied 70 through the said windings of relay 177 in series with the line H and the telephone T12. The operator may listen-in on the telephonic service through the cord-pair Fig. 13 by manipulating listening key 178. The outside springs of said 178 lead to terminals 75 870 and 871 of operator's circuit T8.

Assume, now, that in the stated connection through the cord-pair Fig. 13 the called subscriber at telephone T12 replaces the receiver 80 before the calling subscriber at telephone T. Relay 177 will de-actuate and the described circuit will be re-established from sleeve 172 of springjack 102, sleeve 173 of plug 166, armature 174, lamp 175 to grounded battery, 85 lamp 175 re-glowing as a disconnect signal.

Assume that the calling subscriber at telephone T replaces the receiver first. Then, as has been described, the equipment involved in G is released (regardless of whether selector F or repeater D or repeater E is directly co-operating with G as described hereinbefore), so ground will be removed from conductor 724, leading to sleeve 866 of springjack 863, sleeve 170 of plug 161 90 and to the winding of relay 171, relay 171 de-actuating. A circuit can now be traced from grounded contact 180, conductor 181, armature 182, lamp 183, to grounded battery, lamp 183 glowing. This will serve as 95 100 a disconnect signal for plug 161, so it may be withdrawn.

The line H is shown leading to an individual springjack. Of course, any of the well known means of terminating manual lines in a plurality of springjacks can be substituted, and in fact, lines operated automatically, also accessible to manual switching equipments, as are well known, may be readily substituted.

It is manifest that if selector Fig. 8 of my pending application Serial No. 171,637, filed May 29, 1917, is substituted for selector F herein, upon the trunk being seized through repeater D or through repeater E from the first level of selector B, the cited selector will be caused to rotate-in automatically and seize a trunk on its normal level, without first stepping off-normal vertically. The trunks leading from the said normal level 110 may be the trunks described as leading from the third level of the selector F. Under the arrangement employing the normal level selector Fig. 8, in the cited pending application, the call will be completed to the wire-chief's desk automatically upon seizing the leading-in conductors of repeater E, and that therefore, the last digit "3" will not be sent, as when the trunks leading to the wire-chief's desk lead from the third bank level 115 120 125 130

as described hereinbefore with relation to Fig. 7.

The scope of the present invention, in view of possible modifications and adaptations will be comprehended in view of the subjoined claims.

I claim:—

1. In a telephone system calling and called lines, an operator's switchboard, automatic switches directly controlled from the calling line for interlinking a connection from the calling line to the switchboard, a transfer switch in a Y branch intermediate of the calling line and the switchboard for extending a connection from the calling line to a called line, and means in control of the switchboard for effecting at will a switching operation of the transfer switch and thereafter extending the connection from the calling line and switchboard to the called line.

2. In a telephone system calling and called lines, an operator's switchboard, automatic switches controlled from the calling line for interlinking a connection from the calling line to the switchboard, a transfer switch for extending a connection from the calling line to a called line, means in control of the switchboard for effecting at will a preliminary switching operation of the transfer switch and thereafter extending the connection through the transfer switch from the calling line and switchboard to the called line wherein the said transfer switch is a link, and means controlled at will from the switchboard for temporarily disconnecting and reconnecting the calling line from the established connection including the called line without restoring the transfer switch.

3. In a telephone system calling and called lines, an operator's switchboard, automatic switches controlled from the calling line for interlinking a connection from the calling line to the switchboard, a transfer switch the talking paths of which are in a normally disconnected Y branch from the said connection for extending a talking connection from the calling line to a called line, means in control of the switchboard for effecting at will a preliminary switching operation of the transfer switch and thereafter directly extending the talking connection over the Y branch from the calling line and switchboard to the called line, and means controlled from the switchboard for disassociating the branch extending to the switchboard at will without restoring the transfer switch.

4. In a telephone system calling and called lines, an operator's switchboard, automatic switches controlled from the calling line for interlinking a connection from the calling line to the switchboard, a transfer switch in a normally disconnected Y branch from the calling line for extending a connection from the calling line to a called

line, means in control of the switchboard for effecting at will a preliminary switching operation of the transfer switch to connect same and thereafter directly extending the connection from a point of the connection intermediate of the calling line and switchboard to the called line, and means controlled from the switchboard for temporarily disconnecting the calling line from the established connection while the connection is being directly extended to the called line.

5. In a telephone system calling and called lines, an operator's switchboard, automatic switches controlled from the calling line for interlinking a connection from the calling line to the switchboard, a transfer switch for extending a connection from the calling line to a called line, means in control of the switchboard for effecting at will a preliminary switching operation of the transfer switch and thereafter extending the connection from a Y branch of the connection between the calling line and switchboard to the called line, and means controlled at will from the switchboard for temporarily disconnecting the calling line from the established connection including the called line without restoring a said switch of the linked connection.

6. In a telephone system, stations on calling and called lines, an automatic switch, a pair of companion automatic switches, an operator's switchboard, means controlled from the calling line whereby the calling line can directly progress the call from the said calling line through the individual switch to a called line or alternatively through one of said pair of switches to the said called line or to the said switchboard, means controlled from the switchboard for operating the other switch of said pair over the extension to the switchboard for introducing the called line as a Y branch intermediate of the connection from the calling station to the switchboard, means controlled from the switchboard over its extension for disconnecting the calling line station from talking relation with the connection to the called line while maintaining a talking relation between the switchboard and the called line station, and means controlled at will from the switchboard for reconnecting the calling line station.

7. In a telephone system calling and called lines, an operator's switchboard, automatic switches controlled from a station on the calling line for interlinking a connection from the calling line to the switchboard, a transfer switch for connection in a Y branch of the said connection for extending a connection from the calling line to a called line, means in control of the switchboard for effecting at will a preliminary switching operation of the transfer switch and there-

after directly extending the connection from the calling line and switchboard through the transfer switch to the called line, and means for audibly indicating to the station on the calling line that the call is being extended under control of the switchboard.

8. In a telephone system calling and called lines, an operator's switchboard, automatic switches controlled from a station on the calling line for interlinking a connection from the calling line to the switchboard, a transfer switch in a Y branch of the said connection for extending a connection from the calling line to a called line, means in control of the switchboard for effecting at will a switching operation of the transfer switch and thereafter directly extending the connection through the transfer switch from the calling line and switchboard connection to the called line, and means for applying audible impulses to the station on the calling line corresponding to the directive control impulses applied effective to directly extending the call in the direction of the called line.

9. In a telephone system calling and called lines, an operator's switchboard, automatic switches, means on the calling line for controlling the switches whereby a call can be alternatively extended from the calling line to either the called line or to the switchboard at will, a signal device on the switchboard operative to indicate the extension of the call from the calling line to the switchboard, means for operating the said switches over the extension to the switchboard to complete a connection from the calling to the called line, means controlled from the calling line for effacing the call while the call is being extended under control from the switchboard, and a second signal device on the switchboard operative to indicate that the extended call has been effaced.

10. In a telephone system calling and called lines, an operator's switchboard, automatic switches including a pair of companion selector switches, means on the calling line for directly controlling the establishment of a connection through a first one of said pair of switches in attaining connection with the switchboard, and means on the switchboard for preparing a second one of the said pair of switches whereby it may be directly operated to extend the calling line in the direction of the called line.

11. In a telephone system calling and called lines, an operator's switchboard, automatic switches including a pair of companion selective switches normally operatively disassociated, means on the calling line for directly controlling the establishment of a connection through a first one of said pair of switches in attaining connection

with the switchboard, and means on the switchboard operable at will for preparing a second one of the said pair of switches whereby it may be directly operated from the switchboard to extend the calling line in the direction of the called line.

12. In a telephone system calling and called lines, an operator's switchboard, automatic switches including a pair of companion switches, means on the calling line for directly controlling the establishment of a connection through a first one of the said pair of switches in attaining connection with the switchboard, means on the switchboard for preparing a second one of the said pair of switches whereby it may be directly operated to extend the calling line in the direction of the called line, and means controlled from the switchboard for restoring the first one of the pair of switches from its relation with the extension to the switchboard, leaving the calling and called lines interlinked through the second one of the pair of switches as a link thereof.

13. In a telephone system calling and called lines, an operator's switchboard, automatic switches including a pair of companion switches independently operative, means on the calling line for directly controlling the establishment of a connection through a first one of the said pair of switches in attaining connection with the switchboard, means on the switchboard for directly operating a relay to place a second one of said pair under step control of the switchboard, and means on the switchboard for directly operating the second one of the pair and successively linked co-operating switches whereby the called line may be introduced into a Y branch of the first established connection between the calling line and the switchboard.

14. In a telephone system, stations on calling and called lines, a pair of companion automatic switches, an operator's switchboard, means controlled from the calling line whereby the calling line can directly progress the call from the said calling line through one of said pair of switches to the called line or to the said switchboard, means controlled from the switchboard for operating the other switch of said pair over the extension to the switchboard for introducing the called line as a Y branch intermediate of the connection from the calling station to the switchboard, means controlled from the switchboard over its extension for disconnecting the calling line station from talking relation with the connection to the called line while maintaining a talking relation between the switchboard and the called line station, and means controlled at will from the switchboard for reconnecting the calling line station.

15. In a telephone system calling and

called lines, an operator's switchboard, automatic switches including a pair of companion switches independently operative, means on the calling line for controlling the establishment of a connection through a first one of the said pair of switches in attaining connection with the switchboard, means on the switchboard for operating a relay to place a second one of said pair under step control of the switchboard, and means on the switchboard for directly operating the second one of the pair and successively linked co-operating switches whereby the called line may be introduced into a Y branch of the first established connection between the calling line and the switchboard and the switchboard extension thereafter disconnected at will.

16. In a telephone system calling and called lines, an operator's switchboard, automatic switches including a pair of companion switches, means on the calling line for controlling the establishment of a connection through a first one of the said pair of switches in attaining connection with the switchboard, means on the switchboard for operating a relay to place a second one of said pair under directive control of the switchboard, means on the switchboard for operating the second one of the pair and successively linked co-operating switches whereby the called line may be introduced into a Y branch of the first established connection between the calling line and the switchboard, and means at the switchboard operative at will for disassociating the interlinked extension to the switchboard.

17. In a telephone system calling and called lines, an operator's switchboard, automatic switches including a pair of companion step directed switches, means on the calling line for controlling the establishment of a connection through a first one of the said pair of switches in attaining connection with the switchboard, means on the switchboard for operating a relay to place a second one of said pair of switches under step directive control of the switchboard, and means on the switchboard for directly operating the second one of the pair and successively linked co-operating switches whereby the called line may be introduced into a Y branch of the first established connection between the calling line and the switchboard and the switchboard thereafter at will disconnected by the restoration of the said first switch.

18. In a telephone system, stations on calling and called lines, a pair of automatic switches, an operator's switchboard, means controlled from the calling line whereby a call can be directly progressed from the said calling line through one of said pair of switches directly to the said called line or alternatively directly to the said switch-

board, means controlled from the switchboard for operating the other switch of said pair over the alternative extension to the switchboard for introducing the called line in a Y branch intermediate of the connection from the calling line station to the switchboard, means controlled from the switchboard at will after a three-party talking connection has been established between the calling line station the switchboard and the called line station for disconnecting the branch leading to the calling line station, leaving the switchboard and the called line station in talking relation, and means controlled from the switchboard for thereafter reconnecting the calling and called line stations and the switchboard so a three-party connection will again ensue which involve the same paths as before.

19. In a telephone system calling and called lines, an operator's switchboard, automatic switches including a pair of permanently companion switches, means on the calling line for controlling the establishment of a connection through a first one of the said pair of switches in attaining connection with the switchboard, means controlled from the switchboard for operating the second one of the pair and successively linked co-operating switches whereby the called line may be introduced into a Y branch of the first established connection between the calling line and the switchboard, and means on the switchboard operable at will effective to restore the said second switch and its successively co-operating switches without destroying the established connection from the calling line to the switchboard.

20. In a telephone system calling and called lines, an operator's switchboard, automatic switches including a pair of companion switches, means on the calling line for controlling the establishment of a connection through a first one of the said pair of switches in attaining connection with the switchboard, means controlled from the switchboard for operating the second one of the pair and successively linked co-operating switches whereby the called line may be introduced into a Y branch of the first established connection between the calling line and the switchboard, and means on the switchboard operable at will before or after the connection to the called line is completed effective to disassociate the called line without destroying the established connection from the calling line to the switchboard.

21. In a telephone system calling and called lines, an operator's switchboard, automatic switches including a pair of permanently interlinked companion switches, means on the calling line for controlling the establishment of a connection through a first one of the said pair of switches in attaining connection with the switchboard, means con-

trolled from the switchboard for operating the second one of the pair whereby the called line may be introduced into a Y branch of the first established connection between the calling line and the switchboard, and means on the switchboard operable at will effective to disconnect the calling line from the talking connection established between the switchboard and the called line without restoring any said automatic switches.

22. In a telephone system calling and called lines, an operator's switchboard, automatic switches including a pair of permanently interlinked companion switches normally operatively disconnected, means on the calling line for controlling the establishment of a connection through a first one of the said pair of switches in attaining connection with the switchboard, means directly controlled from the switchboard for operating the second one of the pair whereby the called line may be introduced into a Y branch of the first established connection between the calling line and the switchboard, and means directly controlled from the switchboard operable at will for disconnecting and reconnecting the talking relation of the calling line with respect to the connection established to the called line.

23. In a telephone system calling and called lines, an operator's switchboard, automatic switches including a pair of companion switches, means on the calling line for controlling the establishment of a connection through a first one of the said pair of switches in attaining connection with the switchboard, means on the switchboard effective for operating the second one of the pair and successively linked co-operating switches whereby the called line may be introduced into a Y branch of the first established connection between the calling line and the switchboard, and means on the switchboard operable at will after a Y talking connection has been established between the calling and called lines and the switchboard effective to disconnect the called line and restore the said second switch.

24. In a telephone system, stations on calling and called lines, a pair of automatic switches, an operator's switchboard, means controlled from the calling line whereby a call can be directly progressed from the said calling line through one of said pair of switches directly to the said called line or alternatively directly to the said switchboard, means controlled from the switchboard for operating the other switch of said pair over the alternative extension to the switchboard for introducing the called line in a Y branch intermediate of the connection from the calling line station to the switchboard, and means controlled from the switchboard at will after a three-party talking connection has been established between

the calling line station the switchboard and the called line station for disconnecting the branch leading to the calling line station, leaving the switchboard and the called line station in talking relation.

25. In a telephone system calling and called lines, an operator's switchboard, automatic switches including a pair of companion switches, means on the calling line for controlling the establishment of a talking connection between the said calling line and the said switchboard including a first one of the said pair of interlinked switches, means at the switchboard for temporarily disconnecting the calling line from talking connection with the switchboard at will and for then operating the second one of the pair of companion switches to extend the connection in the direction of the called line and for reestablishing the said talking connection, and means controlled from the calling line for restoring the switches of the connection at will regardless of the state of the switches of the connection.

26. In a telephone system calling and called lines, an operator's switchboard, automatic switches including a pair of companion switches, means on the calling line for controlling the establishment of a connection between the said calling line and the said switchboard including a first one of the said pair of companion switches, and means at the switchboard for temporarily disconnecting the calling line at will without restoring the said first switch and thereupon operating the second one of the pair of companion switches to extend the connection from the calling in the direction of the called line.

27. In a telephone system, stations on calling and called lines, automatic switch mechanism, an operator's switchboard, means controlled from the calling line whereby a call can be directly progressed from the said calling line through the said switch mechanism to the called line or alternatively directly progressed to the said switchboard, means controlled from the switchboard for operating the switch mechanism over the extension to the switchboard for introducing the called line as a Y branch intermediate of the connection from the calling line station to the switchboard, means controlled from the switchboard over its extension for disconnecting the calling line station from talking relation with the connection during the time the extension towards the called station is being effectuated, and means for thereafter reconnecting the calling line.

28. In a telephone system, stations on calling and called lines, automatic switch mechanism, an operator's switchboard, means controlled from the calling line whereby a call can be progressed from the said calling line

through the said switch mechanism to the called line or alternatively progressed to the said switchboard, means controlled from the switchboard for operating the switch mechanism over the extension to the switchboard for introducing the called line as a Y branch intermediate of the connection from the calling line station to the switchboard, means controlled from the switchboard over its extension for disconnecting the calling line station from talking relation with the connection during the time the extension towards the called station is being effectuated, means for thereafter reconnecting the calling line, and means constantly in control of the calling station for destroying the established connection.

29. In a telephone system, stations on calling and called lines, automatic switch mechanism, an operator's switchboard, means controlled from the calling line whereby a call can be progressed from the said calling line through the said switch mechanism to the called line or alternatively progressed to the said switchboard, means controlled from the switchboard for operating the switch mechanism over the extension to the switchboard for introducing the called line as a Y branch intermediate of the connection from the calling line station to the switchboard, means controlled from the switchboard over its extension for disconnecting the calling line station from talking relation with the connection during the time the extension towards the called station is being effectuated, means for thereafter reconnecting the calling line, and means constantly in control of the calling station for destroying all links of the established connection.

30. In a telephone system, calling and called lines, an operator's switchboard, an automatic switch controlled from the calling line for interlinking a connection from the calling line to the switchboard, a transfer switch auxiliary to the first said switch, the talking path of the transfer switch being in a normally disconnected branch of the said connection, the said transfer switch for extending a talking connection from the calling line to a called line, means in control of a first directive means at the switchboard over the established extension from the calling line to the switchboard for effecting a preliminary connecting operation between the first said switch and the transfer switch at will whereby the transfer switch can be thereafter directly controlled by a second means at the switchboard not equivalent in operative effect to the first said means to link the calling line to a called line in talking relation in which the said transfer switch is a link of the connection, and means directly operated from the switchboard for disconnecting the said automatic switch and extension to the switchboard leaving the

calling line and called line connected in talking relation.

31. In a telephone system, telephone lines, a pre-selector, automatic switches, means for operating the switches to extend a connection to a called line from a calling line and obtain a response on the said called line, means normally in control of the calling line for releasing any of the switches of the connection to normal at will regardless of the responded or non-responded state of the called line, and means on the called line operable at will over a talking conductor of the called line to disable the said switches of a connection from releasing under control of the calling line.

32. In a telephone system, telephone lines, automatic switches, means for operating the switches to extend a connection to a called line from a calling line, means for effecting a response on the called line, means normally in control of the calling line for releasing any of the switches of the connection to normal at will regardless of the responded or non-responded state of the called line, and means on the called line operable at will to disable the said switches of a connection from releasing under control of the calling line.

33. In a telephone system, calling and called lines, an operator's switchboard, an automatic switch controlled from the calling line for interlinking a connection from the calling line to the switchboard, a transfer switch auxiliary to the first said switch, the talking path of the transfer switch being a normally disconnected branch of the said connection, the said transfer switch for extending a talking connection from the calling line to a called line, means in control of a first directive means at the switchboard over the established extension from the calling line to the switchboard for effecting a preliminary connecting operation between the first said switch and the transfer switch at will whereby the transfer switch can be thereafter directly controlled by a second means at the switchboard not equivalent in operative effect to the first said means to link the calling line to a called line in talking relation in which the said transfer switch is a link of the connection whereby a three-party Y talking connection will ensue, and means under directive control of the switchboard operator for disconnecting and reconnecting the calling line with relation to the said three-party connection without disconnecting the called line from talking relation with the switchboard.

34. In a telephone system, telephone lines, a pre-selector, automatic switches, means for operating the switches to extend a connection from a calling to a called line, means for effecting a response on the called line, means normally in control of the calling line

for releasing an established connection regardless of the responded or non-responded state of the called line, and means on the called line for disabling the calling line for controlling the release of the connection.

35. In a telephone system telephone lines, a pre-selector, an automatic switch, means for operating the pre-selector and switch in extending a connection from a calling to a called line, releasing means normally in control of the calling line for releasing an established connection, means for effecting a response on the called line, and means on the called line for controlling the releasing means in control of the calling line regardless of the responded or non-responded state of the called line.

36. In a telephone system, calling and called lines, an operator's switchboard, an automatic switch controlled from the calling line for interlinking a connection from the calling line to the switchboard, a transfer switch auxiliary to the first said switch, the talking path of the transfer switch being a normally disconnected branch of the said connection, the said transfer switch for extending a talking connection from the calling line to a called line, means in control of a first directive means at the switchboard over the established extension from the calling line to the switchboard for effecting a preliminary connecting operation between the first said switch and the transfer switch at will whereby the transfer switch can be directly controlled thereafter by a second means at the switchboard not equivalent in operative effect to the first said means to link the calling line to a called line in talking relation in which the said transfer switch is a link of the connection whereby a three-party Y talking connection will ensue, and means under directive control of the switchboard operator for disconnecting the called line and thereafter introducing another called line therefor whereby a three-party Y talking connection will ensue between the calling line the switchboard and the said second called line.

37. In a telephone system, calling and called lines, an operator's switchboard, an automatic switch controlled from the calling line for interlinking a connection from the calling line to the switchboard, a transfer switch auxiliary to the first said switch, the talking path of the transfer switch being a normally disconnected branch of the said connection, the said transfer switch for extending a talking connection from the calling line to a called line, means in control of a first directive means at the switchboard over the established extension from the calling line to the switchboard for effecting a preliminary connecting operation between the first said switch and the transfer switch at will whereby the transfer

switch can be directly controlled thereafter by a second means at the switchboard not equivalent in operative effect to the first said means to link the calling line to a called line in talking relation in which the said transfer switch is a link of the connection.

38. In a telephone system telephone lines, a pre-selector, automatic switches, means for operating the pre-selector and switches to extend a connection from a calling one to a called one of said lines, means for effecting a response on the called line, means normally in control of the calling line for restoring the pre-selector to normal, and means on the called line operable at will over a talking conductor of the called line for preventing the pre-selector from restoring under control of the calling line regardless of the responded or non-responded state of the called line.

39. In a telephone system, calling and called lines, automatic switching mechanism, means on the calling line for controlling the said mechanism for establishing a talking connection to a first called line, means on the called line for controlling said mechanism for establishing a Y talking connection between the said calling and called and a second called line, and means controlled from the first said called line for disconnecting the first said calling line from the said connection leaving the first said called line and the said second called line in talking connection.

40. In a telephone system, calling and called lines, automatic switching mechanism, means on the calling line for controlling the said mechanism for establishing a talking connection to a first called line, means on the called line for controlling said mechanism for establishing a Y talking connection between the said calling and called and a second called line, means controlled from the first said called line for disconnecting the first said calling line from the said connection leaving the first said called line and the said second called line in talking connection, and means controlled from the first said called line for reestablishing the said Y connection.

41. In a telephone system, calling and called lines, automatic switching mechanism, means on the calling line for controlling the said mechanism for establishing a talking connection to a first called line, means on the called line for controlling said mechanism for establishing a Y talking connection between the said calling and called and a second called line, means controlled from the first said called line for disconnecting the first said calling line from the said connection leaving the first said called line and the said second called line in talking connection, and means controlled from the first

said called line for reestablishing the said Y connection without disconnecting the said second called line.

42. In a telephone system, calling and 5 called lines, automatic switching mechanism, means on the calling line for directive- 10 ly controlling the said mechanism for establishing a talking connection to a first called line, means on the called line for controlling 15 said mechanism for establishing a Y talking connection between the said calling and called and a second called line, and means controlled from the first said called line for disconnecting the first said calling line from 20 the said connection leaving the first said called line and the said second called line in talking connection.

43. In a telephone system, calling and 25 called lines, an operator's switchboard, automatic switches, means on the calling line for controlling the establishment of a connection in the direction of the switchboard, means for effecting a response on the called line, means for normally restoring the suc- 30 cessively interlinked switches under control of the calling line, and means at the switchboard operable at will for disabling the said interlinked switches of the connection from restoring regardless of the re- 35 sponded or non-responded state of the called line.

44. In a telephone system, a calling line, 40 a called line, an operator's switchboard, a trunk line terminating in a pair of auto- 45 matic switches, automatic switching means controlled from the calling line for extending the calling line into connection with the trunk line, directive control means on the calling line whereby a first switch of said 50 pair can be directly operated to extend a connection from the calling line through the said switch to the switchboard, means at the switchboard for directly controlling the operation of the second switch of said pair 55 for extending a Y branch from the first said connection to the called line whereby a three- 60 party talking connection will ensue over the Y-branched connection, and means controlled at will from the switchboard for dis- 65 connecting the calling line branch leaving a two-party talking connection between the switchboard and called line.

45. In a telephone system, calling and 55 called lines, a station on the calling line and the called line respectively, an operator's switchboard, automatic switches, means at the calling station for controlling the establishment of a talking connection through certain ones of the switches to the switch- 60 board, means at the switchboard for controlling other of the automatic switches whereby a called line can be introduced as a Y talking branch of the connection from the calling line station to the switchboard, 65 and means under control of the switchboard

for disabling and thereafter restoring at will the talking condition of the branch to the calling line station without disabling the talking relation between the station on the called line and the switchboard.

46. In a telephone system, calling and 70 called lines, automatic switches, means on the calling line for controlling the establish- 75 ment of a connection through certain of the switches to a first called line, means on the first called line for controlling other of said switches whereby a second called line is introduced into the first established connection, and means under control of the first called line for disconnecting and there- 80 after reconnecting the calling line without destroying the established connection between the said first and second called lines.

47. In a telephone system, calling and 85 called lines, automatic switching mechanism, 90 means on the calling line for controlling the said mechanism for establishing a talking connection to a first called line, means on the called line for controlling said mech- 95 anism for establishing a Y talking connec- 100 tion between the said calling and called and a second called line, and means controlled from the first said called line for disconnecting the first said called line or the said second called line or the calling line from the connection thereby leaving a two-party talk- 105 ing connection between the remaining said lines.

48. In a telephone system, calling and 110 called lines, an operator's switchboard, auto- 115 matic switches, means on the calling line for controlling certain of the switches whereby a call can be extended from the calling line to the switchboard, a signal device on the switchboard which will display to indicate the extension of the call from the calling line to the switchboard, means for effacing the signal consequent to a response at the switch- 120 board, means controlled from the switch- 125 board for operating certain other of the switches by way of extending a connection as a Y branch from the established connection to a called line, and means controlled from the calling line over the first responded connection for again displaying the signal device.

49. In a telephone system, a calling line and an operator's switchboard, automatic switches, means on the calling line for controlling the switches whereby a call can be 120 extended from the calling line to the switch- 125 board, a signal device on the switchboard which will display to indicate the exten- 130 sion of a call from the calling line to the switchboard, means for effacing the signal consequent to a response at the switchboard, and means controlled over the responded connection at will from the calling line for again displaying the signal device.

50. In a telephone system, calling and 130

called lines, an operator's switchboard, automatic switches, means on the calling line for controlling certain of the switches whereby a call can be extended from the calling line 5 to the switchboard, means at the switchboard for disassociating the calling line from the connection and for operating certain of the switches over a portion of the said extended call for extending a connection 10 to the called line, and means for re-connecting and thereafter again disconnecting the calling line at will without restoring any of the automatic switches.

51. In a telephone system, calling and 15 called lines, an operator's switchboard, automatic switches, means on the calling line for controlling certain of the switches whereby a call can be extended from the calling line to the switchboard, means at the switchboard for disassociating the calling line from the connection and for operating certain of the switches over a portion of the said extended call for extending a connection 20 to the called line, and means controlled from the switchboard for re-connecting the calling line at will and for disconnecting the extension to the switchboard at will.

52. In a telephone system, calling and 25 called lines, automatic switching mechanism, means on the calling line for directly controlling the said mechanism for establishing a talking connection to a first called line, means on the called line for controlling said mechanism for establishing a 30 Y talking connection between the said calling and called and a second called line, and means controlled from the first said called line for disconnecting any branch of the 35 said connection thereby leaving a two-party talking connection between the remaining 40 branches of the connection.

53. In a telephone system, calling and 45 called lines, automatic switching mechanism, means for operating the said mechanism to establish a three-party Y talking connection between the calling line and two called lines, and means directly controlled from one of the lines of the said connection for disconnecting any said line 50 branch of the connection at will leaving the other two said lines connected as a two-party talking connection.

54. In a telephone system, lines, automatic switching mechanism, means for 55 directly operating the switching mechanism to interconnect three of the lines in a Y talking connection, and directive means controlled from one of the connected lines effective to directly disconnect any one 60 of the connected lines from the connection at will leaving the other two said lines connected.

55. In a telephone system calling and 65 called lines, an operator's switchboard, automatic switches, other lines accessible through

the switchboard through switching-plug connection, means on the calling line for controlling certain of the switches whereby a talking connection is extended from the calling line to the switchboard, means at the 70 switchboard for causing the disconnection of the calling line from the established talking connection and thereafter reestablish the said talking connection at will, and means at the switchboard for operating certain other of the switches whereby a called line can be introduced into a talking connection with the connection as at first established between the calling line and the switchboard, or the "first" said connection 75 extended to a called line directly accessible to the switchboard through switching-plug connection.

56. In a telephone system, lines, automatic switching mechanism, means for directly 80 operating the switching mechanism to interconnect a plurality of said lines in a star talking connection, and directive means controlled from one of the connected lines effective to directly disconnect any one of the 85 connected lines from the connection at will leaving remaining said lines connected.

57. In a telephone system, lines, automatic switching mechanism terminating a trunk line, automatic switch means for extending 90 one of said lines to the trunk and for thereafter operating said automatic switching mechanism whereby the said one line and a plurality of the other said lines will become connected in star talking connection, and means whereby one of the said lines of the 95 said connection can at will directly disconnect any said line from its connection leaving the other lines of the connection still connected.

58. In a telephone system, lines, automatic switching mechanism terminating a trunk line, automatic switch means for extending one of said lines to the trunk and for thereafter directly operating said automatic switching mechanism whereby the said one line and a plurality of the other said lines will become connected in talking relation with each other over individual 100 branches radiating from a common connecting station, and means whereby one of the said lines of the said connection can at will directly disconnect any said line from its connection leaving the other lines of the connection still connected.

59. In a telephone system, a calling line, a called line, an operator's switchboard, a trunk line terminating in automatic switch mechanism, means controlled from the calling line for extending the calling line into 110 connection with the trunk line, directive control means on the calling line whereby the said mechanism can be directly operated to extend a connection from the calling line through the said mechanism to the called 115 line.

- line or alternatively over a second trunk line to the switchboard, control mechanism interposed in the said second trunk line, means including the said control mechanism controlled from the switchboard when connected for operating the automatic switch mechanism to extend a connection to include the called line, and means including the said control mechanism controlled from the switchboard for disconnecting the calling line whereby a secret connection between the switchboard and called line can be maintained and for thereafter restoring the calling line into the connection at will. 70
60. In a telephone system, a calling line, a called line, an operator's switchboard, a trunk line terminating in switch mechanism, automatic switching means controlled from the calling line for extending the calling line into connection with the trunk line, directive control means on the calling line whereby the said mechanism can be directly operated to extend a connection from the calling line through the said mechanism to the switchboard, control means at the switchboard for directly controlling the operation of the said mechanism over the switchboard extension for extending a Y branch from the first said extended connection to the called line, whereby a three-party talking connection will ensue over the Y-branched connection, and means controlled at will from the switchboard for disconnecting the branch to the calling line leaving a two-party talking connection between the switchboard and the called line. 80
61. In a telephone system, a calling line, an operator's switchboard, a signal device on the calling line at the switchboard, means controlled from the calling line for operatively energizing the signal device, means at the switchboard controlled over an energized local circuit for deenergizing the said device and so maintaining it dependent upon a self-locked circuit path, and means controlled from the calling line for unlocking the said path to cause the signal device to again operatively energize and so maintain. 85
62. In a telephone system, a calling line, an operator's switchboard, a signal device on the calling line at the switchboard, means controlled from the calling line for operatively energizing the signal device as a call signal while energized, operator controlled means at the switchboard for deenergizing the signal device, means at the switchboard for self-locking the signal device to maintain it deenergized and means controlled from the calling line for unlocking the signal device and for causing it to reenergize. 90
63. In a telephone system, a calling line, an operator's switchboard, a signal device on the calling line at the switchboard, 95
- means controlled from the calling line for operatively energizing the signal device as a call signal while energized, operator controlled means at the switchboard for deenergizing the signal device, means at the switchboard for self-locking the signal device to maintain it deenergized out of control of the operator at the switchboard, and means controlled from the calling line for unlocking the signal device and for causing it to reenergize. 100
64. In a telephone system, a calling line, an operator's switchboard, a signal device on the calling line at the switchboard, means controlled from the calling line for operatively energizing the signal device as a call signal while energized, operator controlled means at the switchboard for deenergizing the signal device, means at the switchboard for self-locking the signal device to maintain it deenergized, and means controlled from the calling line for unlocking the signal device and for causing it to reenergize without terminating the call. 105
65. In a telephone system, a calling line, an operator's switchboard, a single device on the calling line at the switchboard, means controlled from the calling line for operatively energizing the signal device as a call signal while energized, operator controlled means at the switchboard for deenergizing the signal device, means at the switchboard for self-locking the signal device to maintain it deenergized out of control of the operator at the switchboard, and means controlled from the calling line for unlocking the signal device and for causing it to reenergize. 110
66. In a telephone system, a trunk line, an automatic switch terminating the far end of the trunk line, two interlinked mutually dependent repeaters associated with the near end of the trunk, switching mechanism for connection to the trunk through one of the said repeaters alternatively, auxiliary control means in the switch mechanism, an operator's switchboard accessible from the said automatic switch, and means depending upon whether the trunk is seized through a specific one of the said repeaters which will adapt the connection so the said auxiliary means can be operated from the switchboard. 115
67. In a telephone system, a trunk line leading to an automatic switch at its far end, two interlinked mutually dependent repeaters associated with the trunk, a called line, a calling line terminating in switch mechanism for connection to the near end of the trunk through one of the said repeaters alternatively, an operator's switchboard accessible from the automatic switch, auxiliary control means in the said switch mechanism for operating the said mechanism under directive control of the switch. 120
68. In a telephone system, a calling line, an operator's switchboard, a signal device on the calling line at the switchboard, 125
- means controlled from the calling line for operatively energizing the signal device as a call signal while energized, operator controlled means at the switchboard for deenergizing the signal device, means at the switchboard for self-locking the signal device to maintain it deenergized out of control of the operator at the switchboard, and means controlled from the calling line for unlocking the signal device and for causing it to reenergize. 130

- board to extend a connection from the calling line to the called line, and means depending upon whether the trunk is seized through a specific one of the said repeaters
- 5 6. in extending the connection to the switchboard which will adapt the connection so that the said switch mechanism can be directly operated from the switchboard to connect with the called line.
- 10 7. 68. In a telephone system, telephone lines, automatic switches, means for operating the switches to extend a connection to a called line from a calling line, means for effecting a response on the called line, means normally in control of the calling line for releasing any of the switches of the connection to normal at will regardless of the responded or non-responded state of the called line, and means on the called line controlled over
- 15 20 the talking conductors thereof operable at will to disable the said switches of a connection from releasing under control of the calling line.
7. 69. In a telephone system, telephone lines, automatic switch mechanism, a trunk line having an automatic switch at its far end and a repeater at its near end, means for extending a calling one of said lines through the said switch mechanism and said automatic switch to a called one of said lines, means normally in control of the calling line to destroy the connection regardless of its connected state, and means including the repeater controlled over the talking conductors of the called line whereby the called line can at will disable the calling line from releasing any link of the connection.
- 25 30 35 40 45 50 55 60 65 70 75 80 85 90 95 100 70 75 80 85 90 95 100
7. 70. In a telephone system a calling telephone on a calling line, called lines, automatic switches, means on the calling line for causing the establishment of a talking connection to a first called said line, means on the called line for controlling the establishment of a talking connection from the first established connection intermediate of the calling telephone and the called line to a second called line, and means on the first called line operable at will effective to disconnect and thereafter at will reconnect the talking connection with the calling line.
71. In a telephone system a calling tele-

phone on a calling line, called lines, automatic switches, means on the calling line for causing the establishment of a talking connection from the calling telephone to a first called line, means on the called line for controlling the establishment of a talking connection from the first established connection intermediate of the calling telephone and the called line to a second called line, and means on the first called line operable at will over a talking conductor of the calling line to disconnect and thereafter at will reconnect the talking connection with the calling line.

72. In a telephone system calling and called lines, an operator's switchboard, automatic switches including a pair of companion directive switches, means on the calling line for controlling the establishment of a connection through a first one of said pair of switches in attaining connection with the switchboard, and means on the switchboard operable at will after responding for preparing a second one of the said pair of switches whereby to extend the calling line through the said second one of said pair in the direction of the called line under directive control of other means on the switchboard.

73. In a telephone system, telephone lines, automatic switches, means for operating the switches to extend a connection from a calling line to a called line, means normally in control of the calling line for restoring any said switch of the connection, and means controlled over a talking conductor of the called line to disable all said switches from restoring by control over the calling line.

74. In a telephone system, telephone lines, automatic switches, means for operating the switches to extend a connection from a calling line to a called line, means normally in control of the calling line for restoring any said switch of the connection, and means manually controlled over a talking conductor of the called line to disable all said switches from restoring by control over the calling line.

In witness whereof, I hereunto subscribe my name this 14th day of May, A. D., 1921.

HERBERT M. FRIENDLY.
